UNITED STATES PATENT OFFICE.

FREDERICK HERB, OF BROOKLYN, NEW YORK, ASSIGNOR, BY MESNE ASSIGNMENTS,
TO R. HOE AND CO., INC., OF NEW YORK, N. Y., A CORPORATION OF NEW YORK.

SHEET-CONTROL MECHANISM.

Application filed May 12, 1924. Serial No. 712,519.

To all whom it may concern:

Be it known that I, FREDERICK HERB, a citizen of the United States, residing at Brooklyn, county of Kings, and State of New York, have invented certain new and useful Improvements in Sheet-Control Mechanism, fully described and represented in the following specification and the accompanying drawings, forming a part of 10 the same.

This invention relates to certain improvements in devices for forwarding paper in the form of a web or sheets cut therefrom and is an improvement on the sheet control mechanism of my prior Patent No. 1,474,364.

As set forth in that patent, in certain types of paper handling machinery, such for instance, as a rotary folder, the web is forwarded to a rotary carrier or folding cylinder and between it and a co-operating abutment, usually a cutting cylinder which acts to cut a sheet from the web. Such carriers are provided with sheet taking devices which may be in the form of pins.

25 These pins, when employed, take the head of each sheet and carry it partially around the cylinder. As the pins take the sheet around, a sheet length is cut from the web. It may happen that there will be a slack 30 in the web which would cause the cutting cylinders to operate too soon and to produce what is technically known as a high cut. This trouble is overcome with the construction shown in my patent above referred 35 to, in which there is provided yielding friction members which act to hold the sheet taut and in proper position for the cutting, these yielding bearers being arranged in fixed relation with the cylinder.

40 It frequently happens, however, that webs of different widths are run on the same machine and bearers are arranged in fixed relation with the cylinder. While suitable for a standard width web, these would not be in 45 the right position for a narrower web, as for instance, where a newspaper is changed, say from six to four columns.

The special object of the present invention is to provide a bearer construction in 50 which the bearer is adjustable widthwise of the member on which it is carried so that it can be adjusted to cover any width web which may be passing through the machine.

55 A further object of the invention is to provide a simple and efficient construction by

which the bearers may be adjustably mounted on the member.

With these and other objects not specifically referred to in view, the invention consists in certain novel parts, arrangements 60 and combination which will be described in connection with the accompanying drawings, and the novel features pointed out in the claims hereunto annexed.

Referring to these drawings,

65 Figure 1 is a side elevation of so much of a rotary sheet carrier as is necessary for an understanding of the invention;

Figure 2 is a cross sectional view on an enlarged scale, the section being taken on 70 the line A—A of Fig. 1, and

Figure 3 is an enlarged face view of the bearer.

Referring now to these drawings, the invention has been illustrated as employed 75 with a rotary folder of a printing machine in which a printed web is cut and folded. It will be understood, however, that the invention is applicable for handling a web or sheets cut therefrom from a source other 80 than a printing machine.

In these drawings, 1 indicates side frames of any suitable character for supporting the parts. In the particular construction illustrated the web W has sheets cut therefrom which are folded by a rotary folder. As 90 illustrated, such a folder is provided in the form of a cylinder 2 supported on a shaft 2' suitably journaled in the side frames 1 of the machine, before referred to. This cylinder is provided with sheet taking devices in the form of sets of pins 3, 4. In the particular construction shown the cylinder is capacitated to take two sheets around and the two sets of pins 3, 4 are carried in 95 arms 5, 6 on operating shafts 7, 8, these shafts being operated to project and withdraw the pins at the proper times through the proper mechanism used for this purpose and not here illustrated. The folding 100 is effected by a rotary folding blade 9 carried on a shaft 10, this blade tucking the product to be folded into the bite of folding off rolls 11, 12. The folding blade is operated as usual in this type of folder by 105 means of a gear 13 on the folding blade shaft, this gear meshing with an internal gear 14 fixedly mounted on the frame of the machine.

Co-operating with this folding cylinder is 110

an abutment between which and the cylinder the sheet is forwarded. In the particular construction illustrated where sheets are to be cut from the web, this abutment is in the 5 form of a cylinder 15 carried on a shaft 16. The cylinder is provided with a cutting blade 17 and the cylinder 2 is provided with the usual co-operating woods 18. As shown, the cylinder 15 is a collecting cylinder, being 10 half the diameter of the folding cylinder and is provided with sheet taking devices in the form of pins 19, it being understood that when collecting, one of the sets of pins on the folding cylinder will 15 be silenced.

In the operation of this type of folder, the leading end of the web is taken by one of the sets of pins, as the pins 3, and carried part way around the cylinder 2. As 20 it gets to the folding off position the cutting blade 17 operates to sever the sheet. It may happen that there is a slack in the web, in which event the cut will come in the wrong place. Furthermore, the whole 25 strain of carrying the sheet is at the pins and in case of a jam, particularly where multiple products are being handled, tears or other injury to the sheet are very liable to happen. In accordance with the invention 30 means are provided for yieldingly engaging the products for preventing this and these means are mounted and arranged so that they may be adjusted widthwise of the cylinder to engage products of different 35 widths.

While the specific construction of these means may be varied, in the particular construction shown, they are in the form of yielding segments which may be conveniently formed of steel strips. These segments are indicated by the numeral 20 and they are, as shown, preferably arranged in sets, two of these sets being provided. These segments may be mounted in either 40 the cylinder 2 or its co-operating abutment, as cylinder 15, but as shown are supported in the walls of cylinder 2. In the best constructions these segments have a bodily yielding movement, being normally projected beyond the cylinder walls so as to engage the paper, but yieldingly mounted so as to yield somewhat if a thick product 45 is passing through the machine. To provide this yielding movement the bearer segments are, as shown, spring seated, being seated against springs indicated by the numeral 21. In the best constructions, furthermore, to afford a good engagement with the product, the segments have a roughened 50 or milled face, as shown at 22 in Fig. 3. In accordance with the invention these segments are mounted in the cylinder so that they may be adjusted widthwise thereof so as to engage the sheet at the margin points, 55 that is, at points between the printed sur-

faces so as to avoid smutting of the sheet. While the specific construction for effecting this may be somewhat varied, the cylinder is provided with one or more recesses 23, 70 two such recesses being shown in the particular construction illustrated, see Fig. 1. The segments are mounted in boxes 24 adapted to have a sliding movement in the recesses and the segments are retained in the boxes by reducing the ends thereof, as 75 shown at 25, these reduced ends taken under flanges 26 forming the top of the box. These boxes 24 are adjustably secured in the cylinder in any suitable manner. In the particular construction illustrated the recesses 23 are provided with longitudinal 80 grooves 27, and the boxes are provided at each side with ears 28 in which are clamping nuts 29. The lower ends of these clamping nuts have (see Fig. 2) oppositely inclined faces 30 which engage the sides of the grooves 27, these grooves being, as shown at 31, undercut to receive the inclined sides of the nuts.

With this construction the bearer segments may be easily and quickly adjusted to any desired position on the cylinder so as to engage margins of sheets of widely varying widths, and a very efficient construction is provided.

The folding cylinder 2 may be driven in any suitable manner, as from a miter gear 32 on the cylinder shaft. The cylinder shaft at its other end also carries a gear 33 which meshes with a gear 34 on the end 100 of a shaft 35 which carries one of the folding rolls, as the roll 11 before referred to. The rolls 11, 12 are intergeared by gears 36 so as to rotate together in opposite directions to fold off the products tucked between them by the folding blade.

With the construction shown and described, a very efficient and easily manipulated device has been provided for handling sheets so as to prevent injury to the sheet and to prevent high cutting when the sheets are cut from the web. While the specific form and means for adjusting the friction segments or bearers have been described in the preferred forms, it will be understood that various forms might be employed and mounted to effect the purposes of the invention, and it will be understood that the invention will include changes and variations in the form and mounting of the 115 bearer segments.

What I claim is:

1. The combination of a rotary carrier having sheet taking devices, a co-operating abutment between which and the carrier a product passes, yielding friction devices carried by one of the members and engaging the product, and means for moving the friction devices widthwise of the surface of the member.

2. The combination of a rotary carrier having sheet taking devices, a co-operating abutment between which and the carrier a product passes, yielding friction devices carried by the rotary carrier, and means for moving the friction devices widthwise of the surface of the carrier.
3. The combination of a rotary carrier having sheet taking devices, a co-operating abutment between which and the carrier a product passes, and yielding friction devices arranged in sets carried by one of the members, each of the friction devices being movable widthwise of the member.
4. The combination of a rotary cylinder having sheet taking devices, a co-operating abutment between which and the cylinder a product passes, recesses in the cylinder, holders movable widthwise in the recesses, and bearer segments mounted in the holders.
5. The combination of a rotary cylinder having sheet taking devices, a co-operating abutment between which and the cylinder a product passes, recesses in the cylinder, holders having a sidewise sliding movement in the recesses, means for locking the holders in adjusted position, and friction segments mounted in the holders.
6. The combination of a rotary cylinder having sheet taking devices, a co-operating abutment between which and the cylinder a product passes, recesses in the cylinder, holders having a sidewise movement in the cylinder, means for locking the holders in adjusted position, and spring seated bearers mounted in the holders.
7. The combination of a rotary cylinder having sheet taking devices, a co-operating abutment between which and the cylinder a product passes, recesses in the cylinder, grooves in the recesses, holders having a sidewise movement in the recesses, means carried by the holder and co-operating with the grooves to secure the holders in the recesses, and bearers in the holders.
8. The combination of a rotary cylinder having sheet taking devices, a co-operating abutment between which and the cylinder a product passes, recesses in the cylinder, grooves in the recesses, holders having a sidewise movement in the recesses, friction bearers in the holders, and means carried by the holders and engaging the grooves for locking the holders in adjusted position.
9. The combination of a rotary folding cylinder having sheet taking pins, a co-operating cutting cylinder between which cylinders a product passes, yielding friction devices located on the folding cylinder in front of the pins, and means for positioning the friction devices at various points widthwise of the surface of the cylinder.
10. The combination of a rotary cylinder having sheet taking devices, a co-operating abutment between which and the cylinder a product passes, holders movable widthwise of the cylinder, and bearer segments mounted in the holders.

In testimony whereof, I have hereunto set my hand.

FREDERICK HERB.
